United States Patent Office

Des. 193,324
Patented Aug. 7, 1962

193,324

SWIM SUIT

Mortimer J. Solomon, 1370 Broadway, New York, N.Y.
Filed Jan. 29, 1962, Ser. No. 68,560

Term of patent 3½ years

(Cl. D3—17)

FIG. 1

FIG. 2

FIG. 1 is a front view of a swim suit showing my new design.

FIG. 2 is a rear view thereof.

The dominant feature of my design resides in the portions shown in solid lines.

I claim:

The ornamental design for a swim suit, substantially as shown and described.
